J. S. Sutton,

Dressing Stone.

Patented June 20, 1836.

1. Patent of James & John Suttell

The Schedule referred to in these Letters Patent and making part of the same, containing a description in the words of the said James Suttell and John Suttell themselves of their Improvement in the Machine for Cutting and facing Stone.

We all to whom these presents shall come: Be it known that we James Suttell of the town of Rockeling, in the County of Steuben and John Suttell of the town of Wiles in the County of Yates, in the State of New York have invented a new and useful improvement in Machine for cutting and facing Stone, and that the following is a full and exact description of the construction and operation of said improvement or machine as invented by us, to wit:—^{and operation of} The crank and shaft by which the cog wheel C and pinion C 1 balance wheel K and shaft. It is caused to make a rotary motion.

The cog C, and C 1, acting upon the hammer halves, because the hammer is H, to raise off from the chisel S. Figure 2. The force of the hammer on their return is strengthened by the action of the spring G, & G. The shaft J is the center of motion of the hammer K. The shaft G, through which the wheel of paper, is drove back by the pressure of the stone against the point of the chisel, as represented by Figure 2. K, the marble or stone E, & L, are springs and iron required in the shaft G, which causes the chisel to act upon the stone with much greater force than it would with the hammer alone.

4. The carriage, B, and B. 4. The head blocks, H, and H. 4. are blocks on which the stone is placed. The blocks H and B. 4. are raised and depressed by means of rods passing through the uprights C, O, and C. 4. Square nuts. This will be more readily understood by Figure 2. C and C. 4. are the uprights H and B. 4. in blocks. K, the stone, i.e., the mold, and the dotted lines represent the rods. Lever bar turned in the posts O, C, L, & S, are crank and screw by which the head blocks B is moved along.

4.

2.

The carriage A. & C. to visit the length of the stone. W the weight by which the carriage is drawn forward, the dotted line represents a rope attached to the rear end of the carriage passing under the pulley I, and over the pulley J. P. H. the crank, shaft and rope by which the carriage is drawn back again. The said improvement or machine to be set in motion and be propelled by either human, animal, water, or steam power.

Sticks may be arranged in front of the chisel to prepare rough stone for the action of the chisel.

What we claim as new, and a novel invention and discovery in the above described machine is the combination of those powers and powers which compose the said machine for the purpose of cutting & facing stone.
